CARPET.

No. 20,314.

Patented Nov. 18, 1890.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 20,314, dated November 18, 1890.

Application filed October 20, 1890. Serial No. 368,750. Term of patent 3½ years.

To all whom it may concern:

Be it known that I, OTTO HEINIGKE, of New Utrecht, Long Island, county of Kings, State of New York, have invented a new and original 5 Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face 15 view of a carpet showing my new design.

My design consists of a body A and border B. The body A consists of conventionalized leaf forms intertwined in form of scrolls. The border B consists of an inner ornamental margin and of leaf forms intertwined in form of scrolls and an outer margin ornamented with flower and fan patterns.

What I claim is—

1. A design for carpets, consisting of the body A, substantially as shown. 25
2. A design for carpets, consisting of the border B, substantially as shown.
3. A design for carpets, consisting of the body A and border B, substantially as shown.

OTTO HEINIGKE.
